UNITED STATES PATENT OFFICE.

DEAN A. BECKWITH, OF NEW YORK, N. Y.

DESIGN FOR A TABLE.

SPECIFICATION forming part of Design No. 25,676, dated June 23, 1896.

Application filed May 11, 1896. Serial No. 591,175. Term of patent 14 years.

To all whom it may concern:

Be it known that I, DEAN A. BECKWITH, a citizen of the United States, residing at the city, county, and State of New York, have

5 invented a certain new and original Design in Tables, of which the following is a full, clear, and exact description, reference being had to the accompanying drawing, wherein the view illustrates my new and original design for tables.

The design consists essentially in a flat-top table of oblong shape, having ornamental legs at its four corners, said legs being braced by semicircular braces which are connected together, as shown.

In the drawing, A indicates the flat top of the table, whose edges are ornamented with a molding.

B indicates the side panels, which are plain throughout their length, and C the end panels, which are also plain.

D indicates the legs, whose upper ends are

ornamented by beads and moldings. These legs are cylindrical in cross-section and taper toward their lower ends, which lower ends are ornamented by beads, as shown.

E indicates semicircular braces which connect the end legs of the table and extend toward each other beneath the table, said braces being connected by a straight rod F, 30 said connection being made by ball-shape ends on rod F.

Having thus described the invention, what I claim, and desire to secure by Letters Patent of the United States, is—

The design for a table, substantially as herein shown and described.

I testify whereof I hereunto affix my signature, in presence of two witnesses, this 27th day of April, 1896.

DEAN A. BECKWITH.

Witnesses:

WM. MARKUSKE,
G. J. PALMER.
